UNITED STATES PATENT OFFICE.

JOSEPH A. BLONDIN, OF LOS ANGELES, CALIFORNIA.

PROPELLER.

Application filed March 17, 1925 Serial No. 16,108.

My invention relates to propellers and the method or process for producing the same, said propellers being adapted for use in connection with air or water craft, and also may be used in connection with any motive power associated with a blower or fan.

So far as I am aware, all previous metallic propellers have either been produced from castings, necessitating complicated and intricate molds, or they have been composed of metallic blades secured to arms, or to a separate hub section. In other cases said propellers have been composed of sheet metal faces welded together to simulate more or less closely the contour and pitch of the conventional wooden propeller.

Another form of previously known metallic propellers comprises a continuous piece of relatively thick plate, formed from a single blank, and having flat blades twisted to form approximately a helical or true screw curve from the hub to the tip of the blade, said blades extending in diametrically opposite directions from each other, so that their attacking edges extend along lines which are tangent to the periphery of the hub section or flanges of the propeller.

As will be obvious, propellers produced in the above ways have numerous disadvantages, one of the main ones being the excessive cost of construction. Moreover, propellers constructed as heretofore suggested have inherent weaknesses which limit their life materially, due in a great measure to the enormous stresses and strains resulting from the centrifugal action caused by the rapidity of their rotation. It may also be stated that the specific manner in which said propellers are constructed not only insures their rapid disintegration, as has been clearly demonstrated in practice, but reduces their efficiency to a marked extent.

It accordingly is an object of my invention to eliminate effectively all the above disadvantages and avoid all costly processes or methods, such as casting, molding, or other foundry or machine methods heretofore used in the production of propellers or fan blades of any sort.

Another object of my invention is to provide a novel form of propeller of the straight pitch type, the blades of which do not present any helical twist at their hub section, or at any extensions from said hub section, thus eliminating the practically prohibitive

expense of providing special torsion producing or stamp and die machinery for effecting such a helical twist.

A further object of my invention is to provide a propeller the blades of which, from tip to tip, and also its central hub section, have the same arcuate curve, thus excluding all sections which are flat, and hence, by reason of said curve, overcome all tendency of the blades, while in operation, to flex or bend backward or forward in the line of propulsion under fluid pressure, a fault of propeller blades commonly called "flutter", which is characteristic of all flat bladed propellers.

A still further object of my invention is to provide a novel form of propeller having an improved hub construction which overcomes the faults of propellers of the known type, said faults resulting from clamping the propeller proper between flat-faced hub flanges, where only the friction of said flanges against the propeller hub section can cooperate with the shear resistance of its through-bolts.

More specifically, in my improved propeller the hub section is of arcuate or cambered shape, the front and rear hub flanges having complementary concave and convex surfaces, which, when clamped to the cambered hub section, not only cause the propeller to be driven through the bolts just mentioned, and by reason of the contact friction between said surfaces; but in addition, and mainly through the mass resistance of the propeller material itself, opposing by its cambered or arcuate surfaces any possible independent turning or misalignment of the hub flanges, thus providing for a true lock between the propeller proper and the hub flanges.

Another object of my invention is to provide a novel form of metallic propeller constructed out of a single continuous blank of material, or in its laminated type, of several such continuous blank units, superimposed, and held in mutual close contact by the clamping action of a special design set of hub flanges, together with any desired fastening means, such as rivets or auxiliary bolts, traversing said laminations at points exterior to said hub flanges.

It is also an object of my invention to provide a novel form of propeller which obviates entirely the use of special machine shop

tools, and the expensive processes or methods hereinbefore mentioned, and which in use will withstand all centrifugal stresses, without distortion or warping of its blades, and 5 all thrust stresses, without bending or fluttering of said blades, and by reason of the thinness of said blades, and their shape, will reduce power consuming turning resistance to a minimum, and permit an efficient 10 propulsion with a minimum disturbance of the medium, such as air or water, acted upon. A still further object of my invention is to provide a novel process or method of constructing propellers from sheet material. 15 Further objects and advantages of my invention will become more apparent as the description thereof proceeds.

Reference is had to the accompanying drawings in which similar reference characters denote similar parts. In the drawings,

Fig. 1 is a collection of perspective views illustrating the various steps involved in bringing about the construction and method 25 of producing my improved propeller,

Fig. 2 is a fragmentary plan view of the assembled laminated type of my propeller, the arrows indicating the direction of rotation of said propeller,

30 Fig. 3 is a similar view showing a propeller of the same type as that of Fig. 2, but operated in a reverse direction as indicated by the arrows,

Fig. 4 is a plan view of a conventional 25 type of wood propeller,

Fig. 5 is an end elevation of my improved propeller shown applied to the shaft adapted to be driven thereby,

Fig. 6 is a cross sectional view on an enlarged scale through the laminated propeller shown in Fig. 2, and

Fig. 7 is a view similar to Fig. 5, but positioned horizontally, and with certain parts omitted for the sake of clearness.

45 Describing my invention more in detail, my improved method or process in producing propellers constructed of sheet material, as shown in Fig. 1, consists in rolling a blank of sheet material A in tubular form, the dotted lines indicating the manner in which said tubular form is to be cut to produce a set of arched sections, one of which is indicated by the reference letter B. As will be seen, the blank B, which may be of sheet 50 metal, or of any desired sheet material, is arcuate in section, and as long as the desired diameter of the finished propeller. The reference character b is used to indicate the hole drilled in the propeller to accommodate 55 the engine shaft or any other motor with which said propeller is adapted to be associated.

The next step in effecting my improved 60 process is shown at C, which indicates a one-half section removed from each of the op-

posite ends of the blank B, back to a point adjacent the centre.

The reference letter D indicates in its full lines the finished one-piece propeller, the dotted lines indicating the parts removed 70 from the blank B. From this figure it will be readily seen with what facility and ease said propeller may be constructed, without the use of any but a simple cutting tool.

The reference character E shows a view 75 indicated in full lines the finished product of the laminated type of propeller, the various laminations cut as just explained, and superimposed with a hole b ready to accommodate the engine shaft or the shaft of a fan 80 or blower, the dotted lines indicating the portions removed from the blank B.

In Fig. 2 the laminated propeller is shown in complete and assembled form, the blades L, L', and L'' being shown secured together 85 by means of the hub H, comprising a pair of complementary arcuate hub flanges 1 and 2 secured together in any desired manner as by bolts 3. The inner hub flange 2 is provided, either integral therewith or secured 90 thereto in any desired manner, with a cylindrical or other shape projection 4 to accommodate the shaft S. The projection 4 may be tapered internally as shown to accommodate the end of the shaft S, and positioned thereon by means of the driving fit, or any other preferred securing means may be substituted therefor. The end of the shaft S may be provided with a suitable 95 nut to assist in holding the propeller in position.

In Fig. 3 the laminations 1, 1', and 1'' are mounted precisely as shown in Fig. 2, but the propeller is adapted for a reverse 100 movement from that shown in Fig. 2.

As will be seen from Fig. 2, the propeller in said figure has the attacking edges of each blade positioned in direct alignment, resembling closely the wood propeller of conventional type shown in Fig. 4, but deviating therefrom in the design of the leading edges of each blade.

Of course the number of laminations used may be varied, and any number found in practice desirable may be employed; moreover, it is within the province of my invention to use other material than metal, for example, the well known phenol condensation product called, "bakelite" or other material may be substituted for either of these.

It is to be distinctly understood that it is also within the province of my invention to produce my novel form of propeller with other shapes than arcuate, for example, said propeller may be of angular form, if desired, like an angle iron, and if preferred, may be of laminated form as in the case of the arcuate propeller.

While I have shown and described my invention with great particularity, it will be

obvious that the same may be modified throughout a wide range. I therefore do not propose to be limited to the exact details of construction shown and described, ⁵ but reserve the right in practice to make any and all modifications thereof that fall within the scope of the appended claims.

I claim as my invention:

1. In a sheet metal propeller, in combination, an arcuate hub section, an arcuate blade integral with and extending from two sides of said hub section, and sets of additional arcuate blade elements superposed on said blades, and extending a substantial distance ¹⁰ along the length of said blades.
2. In a sheet metal propeller, in combination, an arcuate hub section, an arcuate blade extending in offset relation from said hub section, sets of arcuate blade elements superposed on said blades and adapted to reinforce said blades, so that said propeller will ²⁰ be entirely free from flat areas, and means

for securing said elements to said blades only at said hub section.

3. In a propeller, in combination, a pair ²⁵ of blades, said blades comprising a set of superposed arcuate hub sections and arcuate blade elements extending therefrom in stepped relation, a pair of upper and lower arcuate hub flanges associated with said hub ³⁰ sections and means for securing said hub sections and said flanges together, whereby said hub flanges and said hub sections may coact to form a true lock.

4. In a propeller, in combination, a set of ³⁵ superposed arcuated blade elements of even thickness throughout and stepped both transversely and longitudinally, and means associated with the mid-portion of said elements for securing them together. ⁴⁰

In testimony whereof I have signed my name to this specification.

JOSEPH A. BLONDIN.
